UNITED STATES PATENT OFFICE

WILLIAM SCHROEDER, OF ORANGE, NEW JERSEY, ASSIGNOR TO WESTERN ELECTRIC COMPANY, INCORPORATED, OF NEW YORK, N. Y., A CORPORATION OF NEW YORK

MATERIAL HANDLING APPARATUS

Application filed January 11, 1930. Serial No. 420,064.

This invention relates to a material handling apparatus and more particularly to an apparatus for handling materials in grouped relation.

It has been a practice, in some instances, in hoisting lumber to bind a quantity of lumber upon a trailer by means of a pair of chains or cables which are passed about the pile of lumber and the platform, at either end, and connected at the top by another chain which is engaged by the hook of a crane to lift the load.

An object of the present invention is to provide an apparatus for handling material which will be simple, efficient, convenient and productive of the maximum of safety in operation.

One embodiment of the invention contemplates the provision, in an apparatus for handling lumber or the like, of a pair of normally horizontal balanced arms which are suspended from a crane hoisting cable, and carry at an intermediate point a plurality of chains terminating in several locking hooks for engaging the frame of a trailer. The arms are interconnected at that end farther from the point of suspension by a chain so that when the trailer is lifted from the ground the chain is forced downwardly with reference to the pivotal point of the arms until it bears upon the upper part of the load, thus preventing any shifting of the load.

A better understanding of the invention will be secured from the following detailed description, having reference to the accompanying drawings, forming a part thereof in which

Fig. 1 is a fragmentary top plan view of a tackle, showing one embodiment of the invention;

Fig. 2 is a fragmentary side elevation of the apparatus shown in Fig. 1;

Fig. 3 is an enlarged side elevation of a trailer frame engaging hook constituting part of the invention; and

Fig. 4 is an edge view thereof.

Referring to the drawings in which similar parts are indicated by identical reference numerals, a trailer platform 11 is shown mounted upon a pair of longitudinally ex-

tending channel members or beams 12-12. A centered front wheel 13 and a pair of spaced rear wheels 15-15 are secured to the bottom of the trailer platform by suitable brackets 16-16, in any suitable manner. A quantity 55 of lumber 17 is stacked thereon and, when it is desired to hoist the platform and its load, a locomotive or other suitable type of crane (not shown) is positioned over the trailer, and a tackle 18 including a pair of parallel arms 19-19 each having a plurality of off-centered apertures 20-20 is lowered thereto. The arms 19 are braced by a connecting member 21, consisting of a pair of cross channels or beams 23-23 which are bolted together 65 (Figs. 1 and 2) to embrace between them a lift plate 24 which is apertured to receive a hoisting hook 26 of the crane. The connecting member 21 is secured to the arms 19 by means of a depending portion 27 which is apertured to receive a pivot pin 29 which extends through any selected aperture of the arm 19 in such manner as to permit oscillations of the arm 19 with reference to the connecting member. Each of the arms 19 is provided with 70 an aperture 31, substantially intermediate the ends of the arm, through which projects a downwardly extending U-shaped band 33. The U-shaped band 33 is rigidly secured to the arms 19 by a plurality of bolts 34, 34 and at 75 a lower extremity is provided with an aperture 35 by engagement with which suitable strong flexible cables or chains 37 and 38 may be secured to the arms 19. At an opposite end, 80 each of the chains 37 and 38 is provided with hooks 39-39 for the purpose of engaging the trailer. At the right hand end of the arms they are provided respectively with clevises 85 41-41 which are connected by means of a chain, cable or other strong flexible member 42, preferably of such a length as to permit an appreciable slack therein when secured to the clevises. The arms 19 are connected at their opposite ends by a counter-weighting 90 bar 43 having mounting pins 45-45 at each end. The arms 19 are provided with any desired number of spaced apertures 46, 46 for the purpose of receiving the mounting pins 45, 45 of the counter-weight; in the particular embodiment illustrated a maximum

of six such spaced apertures are shown. Extending the entire length of the arms 20—20 is a pair of stiffening flanges 47—47.

The hooks 39, 39 consist of a body portion 50 having an upper right angular extension 51, the hook being provided with upper and lower lips 53—53 and a recess 54. The body portion 50 of the hook carries a clevis 55 which is rotatable about a pin 57 horizontally extending through the body portions.

To illustrate the operation of the device it may be supposed that it is desired to hoist the trailer from the floor level of a warehouse to an elevated gallery for storage. The hoisting crane which carries the tackle 19 is swung over the loaded trailer and the tackle is suspended immediately above the pile of lumber 17. While in such position the parallel arms 19 are balanced to assume a substantially horizontal position, such as will facilitate their placement relative to the load, by moving the counter-weight 43 from one to the other of the spacing apertures 46, 46, moving it centerward with reference to the length of the arms 19 if the weight of the chains 38 and hooks 39 is insufficient to overcome the weight of the counter-weight 43, or moving it to the extreme end of the arms 19, if it is found that the weight of the suspended chains and hooks 30 tends to raise the counter-weighted end of the arms 19 above a substantially horizontal position. It is important to have the arms 19 substantially horizontal or in other words parallel with the upper surface of the lumber pile 17 in order to insure, when the tackle has been lowered thereupon and slack produced in the hoisting chain of the crane, that it be found to lie true with the pile of lumber comprising the load. This is especially desirable to save labor and time, where, as is usually the case, the weight of the load is sufficiently great and service conditions are sufficiently severe as to require that the tackle be constructed to withstand hard service and be of a heavy construction. In such cases, it is apparent positioning of the tackle relative to the load after the full weight thereof rests upon the top of the load could only be accomplished with great difficulty, if attempted 50 manually by workmen standing on the ground.

It is seldom necessary to change the position of the counter-weight 43 with reference to the apertures 46 once a generally applicable condition is established. The exceptions are in case the size or weight of the chains 37, 38 and 41, or the hooks 39, be varied, or secondly, if the position of the connecting member 21 with respect to its position relative to the center of the arms 19, is altered, as in view of circumstances to be described hereafter.

In order to insure that the tackle 18 is securely fastened to the frame so as to prevent dislodgement therefrom during handling, the 65 special type of hook member 39, is provided.

The body portion 50 of the hook is grasped by the operator and first inclined from the vertical sufficiently to permit the lower portions thereof to be inserted under the longitudinal beams 12 until the beam 12 contacts with the back of the recess 54. The hook is then lifted, causing the beam 12 to be accommodated in the depth of the recess 54. The operator then thrusts the upper part of the hook forward until the extension 51 passes beyond the top of the beam 12 and until the beam contacts with the main body portion 50 along their entire adjacent surfaces. This brings the upper lip 53 beyond the beam after which the operator permits the hook 39 to drop of its own weight, thus engaging the beam between the upper and lower lips 53—53 and the body portion 50 of the hook. The effect of such a construction is to permit the single ground operator to position the four hooks 39 successively, which he is able to do because once a hook is positioned the lips 53—53 insure its maintenance in position around the beam and the operator is thus free to proceed to the next hook without requiring the attention of other operators to insure that all the four hooks are securely in position before the load is lifted.

Due to the fact that the tackle 19 is suspended from a single point, a tendency of the load to tilt if it is inaccurately balanced with reference to the connecting member 21 becomes apparent as soon as the trailer is lifted from the ground. To overcome this, it is desirable to position the connecting member as near as possible to the center of gravity of the load. This may be accomplished by securing the depending portion 27 to the arms 19 at that aperture therein which will give the desired balanced condition. Once a balanced condition is established with reference to a typical load it will thereafter be unnecessary to change the location of the depending member 27 with reference to the arms 19 provided reasonable care is exercised in loading the lumber so as to insure that the connecting member 21 will always be as near as possible to the center of gravity of the load. In practice, it is seldom possible to locate the depending member 27 with sufficient accuracy to prevent the load 19 from tilting slightly when suspended above the ground. Any tendency of the load to shift, due to said tilting, is however, obviated by increasing the friction between the sections of lumber comprising the load.

In order to positively thus prevent shifting of the load, special features of the tackle are provided. As soon as the hooks 39—39 are firmly secured over the beams 12 at the brackets 16—16, the operator of the crane begins to raise the crane hook 26, with the result that the parallel arms 19 are raised until the chains 37 and 38 become taut. The continued elevation of the crane hook 26 con-

tinues to raise the connecting member 21 with the result that the balanced condition of the arms is overcome and they pivot about the pin 29 and the depending member 27. Since the U-shaped band 33 is rigidly secured to that side of the arms 19 which bears the interconnecting flexible member 41, and since the chains 37 and 38 which are connected to the U-shaped band through the aperture 35 are now taut, the continued hoisting of the crane hook 26 causes the flexible member 42 to bear downwardly until it is bound tightly across the top and from side to side of the lumber pile 17. In the arrangement shown in the drawing, wherein it will be noted that the distance between the pin 29 and the U-shaped band 33 is approximately one-third of the distance between the band 33 and the flexible member 41, distributed a downward pressure of approximately 2,000 pounds is applied to the lumber load by the flexible member 41, if the weight of the load including the trailer is approximately 6,000 pounds, as may frequently be the case. Since a downward pressure of considerably less than 2,000 pounds is ample to prevent shifting of the lumber when the trailer is tilted at any angle conceivable under service conditions, a satisfactory margin of safety is provided such as will insure that a device of the character described may be successfully operated by a one man ground crew, it being necessary for him to adjust the hooks 39, 39 in the manner described above.

In Fig. 2 of the drawing, a dotted line representation is included which shows the extreme inclination assumed by the arms 19 where approximately one-half of the usual load of lumber is carried. It will thereby be understood that the tackle is capable of efficient use regardless of the size of the pile of lumber 17, since the arms 19 are free to rotate through a sufficiently large angle as to permit the flexible member 42 to apply pressure upon the top of a load of lumber of any convenient size which may be contained by the platform 11 of the trailer and the connecting member 21. The operator of the hoisting engine, by lifting on the crane hook 26 and forcing the flexible member 41 downwardly against the pile is then free to hoist the loaded platform to any location within reach and through any maneuvers of which the crane is capable without dislodging or causing any shifting between portions of the load. The pressure exerted upon the lumber pile by the flexible member 41 may be varied by changing the position of the connecting member 21. For instance, the pressure may be increased by decreasing the distance between the U-shaped band 33 and the connecting member 21 or it may be decreased by increasing the distance between the band 33 and the connecting member 21. This may be readily accomplished by removing the pin 29 and moving the depend-

ing member 27 into position over any of the apertures provided for that purpose in the arms 19, and inserting the pin 29 to secure it in such position.

Although the invention has been disclosed and described as applied to an apparatus for handling lumber, it is clear that it is susceptible of numerous modifications to adapt it to handle material of a nature and in forms other than that disclosed, and it is intended therefore, that the invention be limited only by the spirit and scope of the appended claims.

What is claimed is:

1. In a material handling apparatus, a platform for supporting the material, a flexible member, and a pivoted arm for carrying the platform including means for retentionally engaging the flexible member with the top of the material.
2. In a material handling apparatus, a tackle comprising a pivoted arm and a flexible member suspended therefrom for engaging the material to prevent shifting thereof when the material is lifted.
3. In a tackle, a pivoted arm, a flexible member suspended therefrom for engaging a load, and means spaced from the pivot point of the arm for tilting the arm to cause the flexible member to retentionally engage the load.
4. In a material handling apparatus, a tackle including a pair of pivoted arms, a flexible member connected thereto for retentionally engaging the material and a second flexible member suspended therefrom for carrying the material and for tilting the arm to cause the first flexible member to engage the load.
5. In a material handling apparatus, a suspension means, an arm pivoted thereto, means associated with one end thereof for normally maintaining the arm horizontal, means secured to the arm on the opposite side of the pivotal point thereof from the suspension means for supporting the material and means associated with the other end of the arm to engage the supported material when the arm is inclined.
6. In a material handling apparatus, a suspension means, a pair of parallel arms pivoted thereto at an intermediate point, material supporting means pivoted to the arms at an intermediate point, and flexible means interconnecting the ends of the arms nearer the pivot of the material supporting means to wrap around a portion of the material when suspended.
7. In a tackle, a pivoted arm, a flexible member suspended therefrom for retentionally engaging a load, and a second member suspended from the arm for tilting the arm to cause the first member to engage the load.
8. In a material handling apparatus, a tackle including a pair of pivoted arms, a

flexible member connected to both arms for retentionally engaging the material and a second member suspended from the pair of arms carrying the material and for tilting the arm to cause the first member to engage the load.

9. In a material handling apparatus, a suspension means, a pair of parallel arms pivoted thereto at an intermediate point, material supporting means pivoted to the arms at an intermediate point, and flexible means interconnecting the ends of the arms nearer the pivot of the material supporting means to closely engage a portion of the material when suspended.

10. In a material handling apparatus, a platform for supporting the material, a flexible member, and a pivoted arm for carrying the platform including means for retentionally engaging the flexible member with the material.

11. In a material handling apparatus, a level platform for supporting the material, a tiltable arm for carrying the platform, a flexible member at one side of the axis of the arm, means for engaging the flexible member with the material when the platform is being carried and a counterweight at the opposite side of the axis of the arm for balancing the arm.

12. In a material handling apparatus, a tackle including a pair of pivoted arms, a flexible member connected thereto for engaging the material and a member suspended therefrom for carrying the material and for tilting the arm to cause the flexible member to engage loads of varying heights.

13. In a material handling apparatus, a tackle including a pair of pivoted arms, a flexible member connected thereto for engaging the material and a member for engaging the material and a member suspended therefrom for carrying the material and for tilting the arm to cause the flexible member to engage the load and to conform closely to the surfaces of loads having irregular contours.

14. In a material handling apparatus, a load supporting member, a member engageable with the load supporting member comprising a recessed hook having portions partially enclosing the recess, the aperture between said portions being narrower than the load supporting member, whereby a partial rotation of the hook is required to engage it with and disengage it from the load supporting member.

In witness whereof, I hereunto subscribe my name this 27th day of December, A. D. 1929.

WILLIAM SCHROEDER.
